UNITED STATES PATENT OFFICE.

WILLIAM H. STEDMAN, OF HARTFORD, CONNECTICUT, ASSIGNOR TO THE MERROW MACHINE COMPANY, OF HARTFORD, CONNECTICUT, A CORPORATION OF CONNECTICUT.

TAKE-UP.

1,173,320.

Specification of Letters Patent. Patented Feb. 29, 1916.

Application filed March 12, 1914. Serial No. 824,213.

To all whom it may concern:

Be it known that I, WILLIAM H. STEDMAN, a citizen of the United States, residing at Hartford, in the county of Hartford, State 5 of Connecticut, have invented certain new and useful Improvements in Take-Ups; and I do declare the following to be a full, clear, and exact description of the same, reference being had to the accompanying 10 drawings, and to the characters of reference thereon.

My invention relates to sewing machines and more particularly to devices that operate to pull off, control and take up the 15 thread thereof.

The object of this invention is to provide a simple and effective take up, pull off and controller for the thread in sewing machines and more particularly in overseaming 20 machines.

In the drawings: Figure 1 is an elevation of my invention including a portion of an overseaming machine to which my invention is shown applied. Figs. 2, 3, and 4 are 25 diagrams, in the same elevation as Fig. 1, showing the operation of the devices of my invention. Fig. 5 is a plan of the Fig. 2. Fig. 6 is a section taken on the line 6—6 of Fig. 2.

30 Like characters of reference throughout the drawings indicate the same parts.

The single embodiment of my invention shown in the drawings is a form especially designed to be applied to the stitch forming 35 mechanism of overseaming sewing machines of the class disclosed in United States Patents Nos. 732,457 and 785,187 granted to me and issued respectively June 30, 1903, and 40 March 21, 1905; and United States Patent to Joseph M. Merrow, No. 591,049 issued October 5, 1897.

Referring again to the drawings, the numeral 1 denotes the needle, 2 the needle carrier pivoted or fulcrumed on the stud 3 and 45 actuated by the crank 4 on the rotating shaft 5 through the agency of the pitman link 6 one end of which link embraces the crank 4 and the other end of which embraces the stud 2^a on the needle carrier 2.

50 The numeral 7 denotes the needle plate, 8 the presser foot which is indicated in the dot and dash lines to more clearly disclose the stitch forming mechanism.

9 indicates a feed dog, 10 the machine

frame, 11 a bracket plate on the said frame 55 and 12 the needle thread tension mounted on the said bracket plate.

The numeral 13 denotes a horizontally reciprocating looper which operates to pass a loop of looper thread, (which thread is 60 herein indicated by the letter L), through the loop of needle thread (which thread is herein indicated by the letter N), that the needle passes through the needle plate. The loop carrier 14 operates with a vibratory reciprocating movement to grasp the loop of thread which the looper 13 has passed through the needle loop and to carry the 65 said loop of thread into the path of the descending needle. The needle, the looper 70 and the loop carrier thus coöperate in a well known manner to form a two thread overseam stitch.

Referring more particularly to my invention I will now proceed to describe in detail 75 the single embodiment shown in the drawings. The crank embracing end of the pitman link 6 is provided with an extension or lug 20 which is recessed, as is well shown in Figs. 5 and 6, for the reception of the end 21 80 of the implement 22. The free end of the implement 22, (i. e., the end that is opposite to the end 21), preferably has the form of an open hook providing a hook end or tongue 85 23, a hook throat or thread engaging passage 24 and the hook mouth 25. The end 21 of the implement is secured in the recess provided in the lug 20 for the reception thereof preferably by a rivet 26 as is best shown in Fig. 6, and the implement 22 is thus carried 90 bodily by the link 6, the throat 24 of the said implement describing an ovate path which path is disposed in a plane parallel to the plane of movement of the link 6 and also parallel to the plane of movement of the 95 needle.

A pair of thread supporting elements, which in the present case are a pair of shanked and eyed studs having the shanks 30 and 31, and the eye portions 32 and 33 100 through which the thread N passes, are mounted on the bracket plate 11 as shown in Fig. 1. These eye portions 32 and 33 will hereinafter be referred to as "eyes 32 105 and 33" for the sake of convenience and brevity.

The location of the "eyes" 32 and 33 is a matter of importance and in the preferred

embodiment, the said eyes are located with relation to the path in which the throat 24 of the implement 22 travels, and the preferred relation of the said eyes and path 5 may best be seen and understood by reference to the drawings wherein it will be noted that a straight line between the eyes 32 and 33 will extend in the general direction of the plane in which the path of the 10 throat 24 lies and that the entire operative portion of the path of the throat 24 preferably lies wholly at one side of the said straight line extending between the eyes 32 and 33.

15 In the operation of my device, which, although it embodies the functions of a pull off, a take up and a thread controller, I will hereinafter refer to for convenience and brevity as a "take up", assuming the same 20 and the threading system of the machine to have been threaded up and applied as shown in Fig. 1, the shaft 5 rotating in the direction indicated by the arrow causes the needle to swing upward and backward from 25 the position in which it is shown in Fig. 1 and causes the implement 22 to travel to the position shown in the Fig. 2 from which position the implement 22 has traveled to the position shown in Fig. 3 by which time 30 the needle has completed its ascent and, during the latter part of its ascent, the needle has pulled the thread out of the straight line between the eye 33 and the point of penetration of the needle thereby supplementing 35 the action of the implement 22. While the implement 22 is passing from the position in which it is shown in the Fig. 3 to the position shown in Fig. 4, the needle, descending, permits the thread to again assume a straight line between the eye 33 40 and the point of penetration of the needle as shown in Fig. 4, and, as the needle, completing its descent passes a loop of thread through the needle plate as shown in Fig. 45 1, the implement 22 travels from the position in which it is shown in Fig. 4 to the

position shown in Fig. 1 thus completing a cycle of operations.

Although the implement 22 and the eyes 32 and 33, in the embodiment used to illustrate the present invention, are shown and have been described as rigidly mounted on their respective supporting or carrying members and thus no relative adjustment is shown provided, this condition usually being desirable, it is obvious that provision for adjusting any one, any combination or all three of the said thread engaging elements will suggest itself to any one skilled in this art and is well within the scope of the present invention.

Having thus described my invention what I claim is:

In combination in a sewing machine mechanism including a curved eye pointed needle, an oscillating needle carrier and a rotating eccentric element: a pitman link connecting the said rotating element with the said needle carrier, a lug projecting from that end of the said link which embraces the said rotating eccentric element, a moving take up implement fixedly mounted on the said lug and projecting outwardly therefrom in the direction of length of the said lug, whereby the thread engaging portion of the said take up implement is carried and actuated in an ovate path; and stationary means for holding and supporting the thread to be operated upon by the take up implement, on two sides of a point in the said ovate path and in a straight line substantially parallel to the plane in which the said path lies, whereby the thread engaging portion of the take up implement is adapted to move along the length of the thread engaged thereby, during the operative movements of the said implement.

WILLIAM H. STEDMAN.
